UNITED STATES PATENT OFFICE.

GEORGE M. GRAHAM, OF CLEVELAND, OHIO.

PAVING-BLOCK.

SPECIFICATION forming part of Letters Patent No. 401,492, dated April 16, 1889.

Application filed November 30, 1888. Serial No. 292,255. (No model.)

To all whom it may concern:

Be it known that I, GEORGE M. GRAHAM, a resident of Cleveland, in the county of Cuyahoga and State of Ohio, a citizen of the United States, have invented a certain new and useful Improvement in Paving-Blocks for Streets, &c.; and I do hereby declare the following to be a full, clear, and complete description thereof.

10 My invention relates to building-blocks or material for various architectural purposes, as well as for street and sidewalk pavements; and it consists of compressed, dried, and hardened blocks of a prismatic form, which may 15 either be used separately or in a group of smaller blocks, forming one homogeneous solid block of artificial stone.

That the invention may be fully understood, reference will be had to the annexed specification and the accompanying drawings, in which—

Figure 1 is a face view of the artificial polygon block of artificial stone above referred to. Fig. 2 is a side elevation of the same, illustrating the side pointed out by the arrow 1. Fig. 3 is also a side elevation of said block, with the side pointed out by the arrow 2. Fig. 4 is an elevation of the opposite side thereof, Plate 1. Fig. 5 is a side view of a solitary 30 prismatic block having a flattened top or face side and angular bottom side. Fig. 6 is a side view of Fig. 5 as seen from the arrows 3 or 4. Fig. 7 represents a top and bottom view of a block, whereof the top as well as the bottom 35 are of angular formation, as subsequently and respectively seen in Figs. 8 and 9, Plate 2.

Like letters of reference denote like parts in the several views and specifications.

The material used for making the blocks 40 above referred to may be varied for certain purposes, but in every instance must possess more or less tenacious, cohesive, and hardening properties, to allow, while in plastic state, of being cast, molded, and compressed in the 45 formations described, said formation, when hardened either naturally or artificially, producing blocks of the desired compactness, durability, and strength for the purposes required.

50 For extended or large constructions the form as represented in Figs. 1, 2, 3, and 4 is

adapted. For smaller constructions or ornaments the individual or separate blocks, as represented in Figs. 5, 6, 7, 8, and 9, may be used to advantage. The forms of the last- 55 named blocks constitute the combination of the first-mentioned polygon blocks—that is, the face and sides thereof resemble in their form a combination of blocks of a prismatic external form similar to that of the individual 60 blocks.

It is the especial form of the individual block and the application of multiple blocks or combinations shown in Plate 1 which constitutes the essential part of my invention. 65

The face or top side, A, of the block is flat, as seen in Figs. 5 and 6, the edges thereof being slightly beveled, as indicated at a. It is hexagonal or six-sided, forming faces B. The bottom is determined by bevels from all sides, 70 breaking joints in a central line, two opposite bevels being equal in size to any of the sides of the block, as seen at C, thus meeting under an angle equal to that of the sides, which is about one hundred and twenty degrees. 75

The bevels D, or planes from B to C, are necessarily triangular, as seen in the figures. Thus the block as represented in Figs. 5 and 6 comprises the hexagonal face A, with the beveled edges a, the six square sides, B, two 80 square bevels, C, equal in size to said sides, and four triangular bevels, D. For structures requiring more than one layer of the blocks above described, the underlaying blocks are constructed as represented in Figs. 85 7, 8, and 9, from which it can be seen that both ends are beveled, which bevels conform to the beveled bottom shown in Figs. 5 and 6.

It is not designed, ordinarily, that the blocks are to be used individually, as shown in Plate 90 2, but in a manner as shown in Figs. 1, 2, 3, and 4, which represent a combined form or multiple of the blocks, Figs. 5, 6, 7, 8, and 9—that is, they form a combination of separate hexagonal blocks, as far as the face side 95 thereof is concerned, whereas the sides and bottom have angular projections and depressions between, but of uniform angles, which are formed by combining the separate blocks into one solid block, as above described. 100

A structure faced with the multiple form of blocks has the appearance of having been

built of so many separate hexagonal blocks, whereas in reality it consists of a comparatively small number of larger blocks, comprising a firm, solid combination of small blocks.

5 The block as represented in Figs. 1, 2, 3, and 4 comprises the equivalent of eighteen separate blocks of Figs. 5, 6, 7, and 8 solidified. The block-faces as grouped or combined are so arranged that the lower profiles 10 thereof form a duplicate of the side opposite to that pointed out by the arrow 1 (see Fig. 2) and a reverse form of the side opposite to that indicated by the arrow 2, as seen in Figs. 3 and 4. Thus the compressed blocks, when 15 set in close proximity to each other—that is, when laid for street-paving or sidewalks, &c.—leave triangular openings or spaces at the end of each intersection, as indicated at *b*. Said spaces, and also the joints or seams, may be 20 filled with asphalt or liquid cement to effect a solid and firm construction with the said blocks.

The advantages in this application of artificial-stone blocks thus constructed are manifold, viz: The joints of contact with these blocks are in every direction supported and braced by the solid form of the adjoining block, owing to the prismoid or angular extensions and depressions interposed one with 25 the other, which strengthens the structure and allows the saving of material in comparison to stone heretofore employed. It also facilitates the laying of the streets and lessens the amount of binding or cementing material 30 used in street-paving. Furthermore, artificial stone of this description gives a unique finished appearance to the structure, in so far that the grooves *a'*, which resemble the beveled edges and seams of the separate united blocks, 35 have the appearance of being a continuation 40 of said bevels and seams, or vice versa. The

actual seams, with little care, can be made to conform with the grooves of the compound blocks, so as to be taken for a part of the hexagonal design of the structure. These 45 seams or beveled edges *a'* prevent horses and other draft-animals from slipping, as the calks of the shoes will catch in the seams, while said seams are not of sufficient size to admit of the calks being held therein more than to 50 prevent slipping on the roadway.

The said blocks are made of a suitable mineral cement first sufficiently reduced to a moist or damp condition, so that when submitted to the power of a hydraulic press in 55 molds conforming to the configuration of the block the cement, when dry, will form a compact, tenacious, and indurated stone of the form and for the purpose herein described.

What I claim as my invention, and desire 60 to secure by Letters Patent, is—

1. As a new article of building material, blocks of artificial stone with two opposite sides analogously formed and the other two inversely, the horizontal and vertical profiles 65 of said sides having extensions and depressions of hexagonal prismoids, the face side thereof being grooved to resemble said prismoids, substantially as shown, and for the purpose described.

2. An artificial-stone block consisting of a prismoid having six square vertical sides, a flat face with broken edges, and an under side beveled to an edge of opposite corners, substantially as shown, and for the purpose 75 described.

In testimony whereof I affix my signature in presence of two witnesses.

GEORGE M. GRAHAM.
